UNITED STATES PATENT OFFICE.

HAROLD F. ELLIOTT AND JAMES ARTHUR MILLER, OF PALO ALTO, CALIFORNIA,
ASSIGNORS, BY MESNE ASSIGNMENTS, TO FEDERAL TELEGRAPH COMPANY, OF
SAN FRANCISCO, CALIFORNIA, A CORPORATION OF CALIFORNIA.

RADIOFREQUENCY SYSTEM.

Application filed January 9, 1922. Serial No. 527,884.

To all whom it may concern:

Be it known that we, HAROLD F. ELLIOTT and JAMES ARTHUR MILLER, citizens of the United States, and residents of Palo Alto, 5 in the county of Santa Clara and State of California, have invented a new and useful Radiofrequency System, of which the following is a specification.

Our invention relates to a radio frequency system, and more particularly to an arc converter system in which a plurality of radio frequency arcs operated either from direct current or from a low frequency source and producing high frequency oscillations, are 10 operated in parallel so as to multiply the load capacity of the system. The parallel operation of converters may be desirable under certain conditions as, for example, when the total load would be too large for 15 one converter, again, when a plurality of arcs of low rating only are available and it is desired to increase the output. The scheme may also be used to advantage in large radio stations in which there are a plurality of 20 arc converters, each designed to communicate with a distant point, there being as many channels of communication as there are converters. By paralleling a plurality of the arcs, an increased power may be obtained, even though temporarily, with a 25 correspondingly reduced number of channels of communication. The combined units may serve to transmit signals for extra long 30 distances, or under severe conditions necessitating greater power. In this way, the flexibility of such an installation can be materially increased.

The parallel operation of arcs may be of further advantage in case they are fed from an alternating current source. If but one such arc is utilized, the amplitude of the current supplied to the oscillatory circuit varies through a regular cycle in accordance with the alternations of the supply voltage. 40 By paralleling arcs fed from different phases of a polyphase system, the amplitude of the oscillations are made to be substantially uniform.

It has been found that the stability and 45 steadiness of operation of a plurality of arcs in parallel under different conditions are

materially enhanced over the operation of a single radio frequency arc converter.

Although these advantages, as well as others, are well known for the parallel 55 operation of arcs, this mode of operation so as to render it satisfactory is ordinarily difficult of maintenance. This arises from the fact that certain conditions must be fulfilled in order that the operation in parallel 60 may be desirable. The arc converters must be kept in synchronism with respect to their output radio frequency currents; they should divide the load between them in any predetermined manner, and their operation 65 should be confined to a predetermined path or frequency. It is one of the objects of our invention to insure the satisfactory operation of converters or other sources of oscillations in parallel.

The invention possesses other advantageous features, some of which, with the foregoing, will be set forth at length in the following description, where there will be outlined in full those forms of the invention 70 selected for illustration in the drawings accompanying and forming part of the present specification. In the drawings, we have shown several embodiments of our invention, but it is to be understood that we do not 75 limit ourselves to such forms, since the invention as expressed in the claims may be embodied in a plurality of other forms.

Referring to the drawings,—

Figure 1 is a wiring diagram of one form 85 of our invention;

Fig. 2 is a wiring diagram of another form;

Figs. 3, 4, 5 and 6 show embodiments of the invention in systems using a polyphase 90 low frequency source for the supply of power to the converter; and

Fig. 7 shows a modification of the forms illustrated in Figs. 1 and 2.

In Fig. 1 the arcs 11 and 12, or other 95 sources of high frequency oscillations, are operated from mains 13, 14 and 15, 16 respectively. These may connect either with a direct current source or an alternating current source of relatively low frequency 100. In order to prevent the high frequency current from flowing through the source, ap-

properiate choke coils 17 and 18 may be provided in the mains. The arcs are enclosed in an atmosphere of hydrogen or other suitable gas, and operate in parallel to supply an antenna circuit comprising antenna 19, inductance 20, and the ground 21. The invention, however, is fully as applicable to other forms of high frequency load. Appropriate means, such as electromagnets 22 and 23, 10 are provided for influencing the operation of the arc in the ordinary manner.

Included in each of the parallel or branch circuits is some form of reactor; in the form shown in Fig. 1 the condensers 24 and 15 25 are used. These condensers have reactances so chosen, so far as their relative values are concerned, as to cause the load to divide properly between the two paths, and they are each great enough so that they form 20 substantially all of the impedance in the path. Thus, if the condensers have reactances that are equal, then both branch circuits carry equal loads. If however, condenser 24 has twice the reactance of condenser 25, then the branch circuit including 25 condenser 24 will supply only half of what the other branch circuit will. Due to the fact that the reactances are high, they serve 30 to synchronize the currents from the two arcs properly, since slight variations in the arc impedance have but little effect upon the total impedance of the circuit. The impedance of the entire antenna circuit may be computed in the ordinary way, taking into 35 consideration the parallel paths through the arcs 11 and 12. The values chosen for the reactances of the condensers 24 and 25 are in a measure dependent upon the required value of the total impedance of the 40 oscillatory circuit.

In addition to synchronizing the arc currents and dividing the load properly, it may be advisable to provide additional means to insure against cross currents between the 45 arcs, or against tendency for the arcs to operate at any other frequency than that desired. Such a device is shown in the present instance at 26 and may consist of two balanced coils 27 and 28, one in each branch circuit, with a common iron core 29. This stabilizes the circuit in a manner described in detail in a copending application, Serial No. 527,885 in our names, entitled Radio frequency system, filed concurrently herewith 50 and assigned to the same assignee as the present invention. Other equivalent schemes therein described may be utilized in lieu of that shown. In short, the arrangement is such that an increased energy loss results as 55 soon as the desired condition of operation is departed from. Thus, in the event of any cross currents, the coils 27 and 28, being so arranged that their magnetomotive forces add for cross currents, produce a strong 60 field through the core 29. This causes a

heavy core loss. For normal operation, the magnetic fields produced by the two coils substantially neutralize each other. Other conditions may be imposed, such as on the frequency, all as described in the application 70 heretofore identified.

Instead of utilizing capacitive reactances for the purpose of synchronizing and for dividing the load, it is possible to use inductive reactances. Such a scheme is shown in Fig. 75 2, wherein the inductors 30 and 31 are inserted in the branch circuits. When these inductors are used, it may become necessary to reduce the inductance 20 of the main oscillatory circuit to compensate for the high 80 inductances of the two coils 30 and 31.

In addition to the coils 30 and 31, use 85 may be made stopping condensers 32 and 33 in order to prevent interference between the sources of supply.

An embodiment of the invention to a system utilizing a polyphase source for exciting the converters is illustrated in Fig. 3. In this case a three phase generator 34 of comparatively low frequency is arranged to supply 90 three arcs 35, 36 and 37. These arcs are connected between the neutral point 38 of the generator 34, here shown as a Y connected machine, and the extremities of the three phases. Choke coils 39, 40 and 41 may be 95 interposed between the arcs and the generator 34 for the usual purpose of preventing the flow of high frequency current through any of the phases of the generator. All the arcs are arranged in parallel to supply a load, such as the antenna load consisting of the earth connection 21, inductor 20, and aerial 19. Inserted in each parallel path is a condenser 42, 43 or 44 which has a sufficiently 100 high reactance to mask the impedance of the remainder of the circuit. As explained in 105 connection with Fig. 1, this has the effect of synchronizing the currents supplied by the three arcs, as well as of insuring proper division of the load. This modification also shows a stabilizing device between each pair of parallel circuits. Thus the coils 45 and 46 have a common core 47 and serve to prevent cross currents between arcs 35 and 36.

The branch circuits of these two arcs are 110 united by conductor 47' connecting to a common point 48 in the antenna circuit. In an entirely similar manner, coils 49 and 50 stabilize the circuit between parallel arcs 36 and 37, and the coils 51 and 52 stabilize the 115 circuit between parallel arcs 35 and 37. It is thus seen that between each pair of parallel arcs a stabilizing device is inserted, the junction points of which are tied together 120 at 48 to a point in the load circuit. The scheme may be readily extended to any number of arcs or other sources of high frequency oscillations operating in parallel.

A simplified scheme for the operation of 125 three arcs in parallel is disclosed in Fig. 4. 130

In this figure the stabilizing devices between the arcs are omitted, the effect of the condensers 42, 43 and 44 in the parallel circuit being proportioned so as to make the use of 5 further devices not absolutely essential.

It is furthermore not essential that each arc should have a separate pair of electrodes. In the modification shown in Fig. 5, a common neutral electrode 53 is provided with 10 which the three electrodes 54, 55 and 56 form the three arcs. Magnetic fields may be utilized in any appropriate manner to influence these arcs. In all other respects this figure is similar to Fig. 4.

15 A modified scheme for insuring load division is shown in Fig. 6. In this figure the parallel arcs 35, 36 and 37 are connected to a stabilizing device 56 which is shown diagrammatically. This device may comprise 20 the sets of coils and cores shown in Fig. 3. In series with arc 35 are the inductor 57 and condenser 60; in series with arc 36, the inductor 58 and condenser 61; in series with arc 37, the inductor 59 and condenser 62. 25 In each arc circuit the condenser and inductor are so proportioned that at the desired frequency of operation, the combined reactance of these two elements is a minimum; in other words, the circuit is tuned to that 30 frequency. In this instance, load division is secured by the proper choice of supply voltages and circuit resistances, which must have the proper relative values in the various circuits. The stabilizing device 56, besides rendering the circuits stable, also synchronizes them, since when the circuits are not in synchronism, the magnetic balance is destroyed, in each pair of coils between the 35 arcs out of synchronism.

40 The application of the last described scheme to a pair of arcs 11 and 12 operating in parallel is illustrated in Fig. 7. In this figure the inductor 64 and condenser 63 in series with arc 11 are tuned to resonance, as 45 well as inductor 66 and condenser 65 in series with the arc 12. A stabilizing device to prevent cross currents is placed in circuit and is diagrammatically illustrated at 26. Here also, proper load division between the two 50 arcs is assured by proper choice of operating voltages and by the resistances in each circuit, which form the total impedances of the circuits, since the inductances and the capacities cancel each other. Synchronism is 55 assured by the action of the stabilizing device 26.

From the foregoing description, it is evident that we have provided novel and useful arrangements whereby arc converters may 60 be efficiently operated in parallel.

We claim:

1. In a radio frequency electrical system, means including a plurality of arcs operating in branch circuits for producing high 65 frequency oscillations, an impedance in se-

ries with each arc of such value that it forms substantially all of the impedance in the branch circuit, and means for preventing cross currents between the arcs, comprising a device arranged to consume a 70 substantial amount of energy when cross currents exist.

2. In a radio frequency electrical system, a plurality of means operating in parallel branch circuits, for producing high frequency 75 oscillations, an impedance in each circuit of such value that it forms substantially all of the impedance in the circuit, and means for preventing cross currents between the branch circuits, comprising a device arranged to 80 consume a substantial amount of energy when cross currents exist.

3. In a radio frequency system, a plurality of means operating in parallel circuits for producing high frequency oscillations, an inductor and a condenser in series with each of 85 said means, each of the parallel circuits being tuned to the frequency of the system in such a way that the reactance is a minimum 90 in each circuit at that frequency, and means for preventing cross currents between the branch circuits, comprising an energy consuming device consuming a substantial amount of energy upon the occurrence of 95 cross currents.

4. In a radio frequency system, a plurality of means operating in parallel circuits for producing high frequency oscillations, an inductor and a condenser in series with each of 100 said means, each of the parallel circuits being so tuned at the frequency which it is desired to use that the total impedance in each of the circuits reduces merely to its resistance, and means for synchronizing the high frequency oscillations in the parallel 105 circuits, comprising an energy consuming device, consuming a substantial amount of energy upon departure from synchronism.

5. In a radio frequency system having a plurality of parallel paths for the current flowing through the load, means for producing high frequency oscillations by an arc located in one of the paths, an inductance coil in the same path as the arc, another inductance coil in a path parallel to the arc, 110 and a common core for these coils, the coils being so arranged that for an appreciable flow of current in a local circuit including the two coils, the core loss is considerable, 115 while when the arc current flows entirely through the load, no appreciable core loss results.

6. In a radio frequency system, means for producing high frequency oscillations by a 120 plurality of arcs arranged in parallel, an inductance coil in each of the parallel paths, and a common core for these coils, the coils being so arranged that for appreciable cross currents between the arcs, the core loss is 125 considerable, while when there is no sub- 130

stantial cross current, no appreciable core loss results.

7. In a radio frequency system, a plurality of means for producing high frequency oscillations connected in parallel relation, an inductance coil in each of the parallel paths, and a common core for these coils, the coils being so arranged that for appreciable cross currents between the means, the core loss is considerable, while when there is no cross current, no appreciable core loss results.

8. In a radio frequency system, a plurality of arc forming electrodes, means for supplying pairs of said electrodes with polyphase current, whereby each pair operates on sep-

arate phases, a common oscillatory load circuit for all of the pairs of electrodes, and means for preventing cross currents between any of the arcs, comprising a pair of inductance coils for each pair of arcs, said inductance coils being located one in each of the two arc circuits, and cores, one for each of said pairs of induction coils, said coils and cores being so arranged that an appreciable core loss results therein only when there are cross currents between the arcs.

In testimony whereof we have hereunto set our hands.

HAROLD F. ELLIOTT.
JAMES ARTHUR MILLER.
